JEWELRY FINDING OR SIMILAR ARTICLE

Alpin Chisholm, Attleboro, Mass.

Application October 30, 1952, Serial No. 22,058

Term of patent 14 years

(Cl. D45—1)

To all whom it may concern:

Be it known that I, Alpin Chisholm, a citizen of the United States of America, residing at Attleboro, in the county of Bristol and Commonwealth of Massachusetts, have invented a new, original, and ornamental Design for a Jewelry Finding or Similar Article, of which the following is a specification, reference being had to the accompanying drawing, forming a part thereof.

Fig. 1 is a front elevational view of a jewelry finding embodying my new design;

Fig. 2 is a side elevational view thereof; and

Fig. 3 is a plan view thereof.

I claim:

The ornamental design for a jewelry finding or similar article, substantially as shown.

ALPIN CHISHOLM.
